UNITED STATES PATENT OFFICE.

JOHN L. MATTHEWS, OF BALTIMORE, MARYLAND.

SMOKE-CLEANING DEVICE.

No. 899,882.

Specification of Letters Patent. Patented Sept. 29, 1908.

Application filed August 19, 1907. Serial No. 389,240.

To all whom it may concern:

Be it known that I, JOHN L. MATTHEWS, a citizen of the United States, residing at Baltimore, in the State of Maryland, have invented certain new and useful Improvements in Smoke-Cleaning Devices; and I do declare the following to be a full, clear, and exact description of the invention, such as will enable others skilled in the art to which it appertains to make and use the same.

My invention relates to an improved smoke cleaning device, and has for its object to more particularly adapt such a device for the use of live steam or air for creating a draft when it is impossible or inconvenient to utilize exhaust steam for such purpose.

It also has for its object to provide means for causing a condensation of the steam and water combined therewith, and also to provide means for more conveniently removing the deposits that accumulate in the apparatus.

With these and other objects in view, the invention consists in the improved construction and novel arrangement of parts of a smoke cleaning device as will be more fully set forth hereinafter.

In the accompanying drawings, which illustrate the invention, Figure 1 is a vertical sectional view of an apparatus embodying my invention; and Fig. 2 is a similar view of a modified form of the same with parts in elevation and parts broken away.

Referring more particularly to the drawings, 1 indicates a chamber or compartment, 35 which may be of any suitable size and dimension, and is adapted to be connected with a fire box, 2, by means of a pipe or conduit, 3. The fire box may comprise any object in which combustion is carried on, as a smelter, 40 or the furnace of a shop or mill, and especially where there is considerable smoke or unconsumed carbon. The cleansing chamber 1 is preferably cylindrical and supported in any suitable manner as by posts, 4, at any 45 suitable height to adapt it for being connected with the fire box and also to permit of its being readily cleansed or opened. While said smoke holder or compartment can be built out of any suitable material in any suitable manner, it is preferably formed of concrete mixed with crushed stone, with an iron netting placed on the inside and inclined or

tapered upward at the top, from which extends a smoke stack, or conduit, 5.

The bottom of the chamber is made watertight for a sufficient depth, and is provided at any suitable point, preferably centrally, with an opening, 6, from which a trap, 7, extends downward. The trap is closed at the top by means of a door, or cover, 8, and has a door, 9, at its lower end, preferably hinged thereto so as to swing downward when opened.

Projecting from one side of the chamber at the level of the water, is an outlet or discharge pipe, 10, which is preferably provided with a valve, 11. Arranged in the sides of the compartment, directly above the top of the water, is a series of openings, which are adapted to be closed to a greater or less extent by suitable doors, 12 which slide in oppositely disposed cleats 13 and are controlled by hand as is desired.

Projecting into the interior of the compartment from one side is a pipe, 14, which is adapted to convey water from any suitable source (not shown) and terminates at its inner end, which projects upward, with a spray head, 15, preferably located directly underneath the entrance to the flue or smoke stack, 80 5. A pipe, 16, extends into the compartment through the wall and communicates with its inner end with the upturned portion, 17, of the pipe, 14, at a suitable distance below the head, 15. The pipe, 16, is adapted 85 to convey steam from any suitable source (not shown), but more particularly live steam, directly from its source so as to deliver the same into the water from the pipe, 14, and to discharge the water into the compartment in the form of a fine, even spray, and with considerable force. A valve 18 may be provided for the inner end of the pipe, 16, and the entrance to both of said pipes is adapted to be controlled by suitable 90 valves, not shown, in convenient position for being controlled by the engineer or person in charge of the works.

A perforated damper, 19, is located in the lower end of the smoke stack, 5, and at a suitable distance from the spray head, 15, which is adapted to engage with the current of steam and water as they are leaving the chamber 1, thereby condensing the same and

causing the condensation to be precipitated into the tank at the bottom of the compartment.

When constructed in this manner, it is evident that my improved cleaning device can be connected with the fire box or top of a smoke stack in any desired manner, as by hermetically connecting the conduit, 3, therewith in a manner similar to that shown in my Patent, No. 824,800, dated July 3, 1906. If, from any cause, the draft from the fire box through the flue, 5, should be deficient, as by the condition of the atmosphere, as with a low barometer, a forced draft can be secured by admitting steam through the pipe, 16. If the steam should lack sufficient moisture, as when live steam is being used, the moisture can be secured by the entrance of water through the pipe, 14, and spray head, 15. In case the desired draft cannot be secured from the foregoing means, a current of air from any suitable source, as a blower, 20, may be introduced through the pipe, 21.

If it be desired to increase the draft to a still greater degree, or at a different point, live steam may be introduced into the conduit, 3, at any suitable point by means of a pipe, 22, which is preferably provided with a nozzle, 23, bent so as to project the jet of steam upward through the conduit. A jet of water may be also introduced into the conduit, 3, as by means of a pipe, 24. With an apparatus as above described, when the smoke from the fire box is delivered into the compartment, its force is destroyed to a certain extent, owing to the larger size of the compartment, and the heavier particles will fall or be deposited in the tank at the bottom of the compartment, the water quenching any of them that may be on fire, thereby preventing the possibility of fire being communicated by the escaping sparks or products of combustion. This settling of the heavier particles or cleansing of the smoke is facilitated by the jet of steam and water that is located in the conduit, 3. As the smoke is drawn or forced out of the compartment by the force of the draft created by the jet of steam from the pipe, 16, the finer particles are moistened thereby to such an extent that they are washed down into the tank at the bottom of the compartment by the condensation that occurs upon the perforated damper.

The draft through the compartment can be also further controlled by means of the openings, 12, near the bottom, and the smoke stack 5 can be extended directly upward and discharged into the atmosphere or it can be extended laterally as shown at 25 in the drawings by means of which it may be ad-

joined, attached to or connected with a smoke stack or chimney in the well known manner. When it is desired to clean out the compartment or to remove the contents of the tank, entrance is had through suitable doors, 26. By removing the cover 8 and opening the door 9, the contents of the tank can be discharged through the trap 7 into any suitable receptacle, as a wagon, or it may be run off into any convenient place by means of a conduit, not shown.

In Fig. 2 I have shown my improvements when used with or applied to a smoke stack, as shown in my said patent, No. 824,800. In this instance, the conduit, 27, is extended downward and connected with the compartment, which is provided with a spray head, or live steam and air jet, in the same manner as shown in Fig. 1, or the compartment may be dispensed with and the conduit extended from its lower end as shown in dotted lines, 28, so as to communicate with any suitable point of discharge, as a running stream, etc., not shown. In either structure, the conduit, 3, or 27, as the case may be, is preferably provided with a suitable door, as 29, by means of which access may be had to the interior of the conduit for the purpose of cleansing it from any soot, or other foreign substances that might accumulate therein.

If desired, the compartment 1 may be large enough to be used in connection with a plurality of furnace or fire boxes, and it may also be provided with a plurality of flues, as shown in dotted lines at 30 in Fig. 2.

As above described, it will be evident that by providing a furnace or smelter with my improved smoke cleaner, the draft can be controlled independently of the condition of the atmosphere, and the furnace, etc., can be made substantially smokeless, that is, the unconsumed carbon that is generally carried out at the top of the smoke stack, will be deposited in the tank at the bottom of the compartment.

Having thus fully described my invention, what I claim as new and desire to secure by Letters-Patent, is:

1. In a smoke cleaning device, a chamber having a body of water in its lower portion and provided with air holes located in the wall of said chamber above the body of water, means for adjustably controlling said air holes, said chamber having a smoke intake opening in the walls thereof above the air holes, water atomizing means located above the smoke intake, and a smoke outlet pipe above said atomizer, substantially as described.

2. A smoke cleaning device comprising a chamber provided with intake and outlet smoke flues, a water supply pipe communicat-

ing with said chamber, a steam pipe communicating with said water pipe near the open end thereof, a damper controlling the outlet smoke flues, said chamber having a plurality of adjustable air inlets adjacent to the bottom thereof, a source of air supply with means for feeding it to the chamber to increase the draft therethrough, steam injectors in the smoke inlet flue and means

for discharging the precipitated matter from the chamber.

In testimony whereof I have hereunto set my hand in presence of two subscribing witnesses.

JOHN L. MATTHEWS.
